PISTON EXPANDER

Edward B. Dennie, Hollywood, Calif.

Application February 24, 1936, Serial No. 65,343

6 Claims. (Cl. 309—12)

This invention relates to an accessory for engines, and particularly pertains to a piston expander.

In various types of engines, especially internal combustion engines, it has become common practice to form the engine pistons of light weight material, and to form a longitudinal slit in the skirt of the piston so that expansion and contraction of the piston may take place without unbinding or wear between the piston and its cylinder. During the use of pistons of this type, however, wear gradually occurs on the outer cylindrical surface of the piston until the piston is loosened within the cylinder and does not fit with the proper tightness. Various devices have been designed to expand the split skirt of the piston so that there will be a proper tight fit between the skirt of the piston and its cylinder. Some of these devices have been in the form of expanding elements having prongs attached to a yielding member, the resilience of which acts to expand the piston at opposite sides of the slit in the piston skirt. Such structures are applied by drilling holes through the skirt of the piston. An example of a device of this character is shown in a patent issued to Charles M. O'Neil, dated March 22, 1932, No. 1,850,214. In a structure of the type shown in the aforesaid patent the expansive action is dependent solely upon the inherent resiliency of the spring of which it is made. There is no way to vary the effectiveness of such an expanding element and no way to maintain it in an adjusted position. It is also desirable to provide a device which will operate without binding and without excessive wear between its various elements. It is the principal object of the present invention, therefore, to provide a piston expanding device which does not depend upon the resiliency of the expanding element for its action, but which is fitted with mechanical adjusting means for directly expanding and holding the piston in its set position and which operates freely with minimum wear.

The present invention contemplates the provision of a ring-shaped member having lugs upon diametrically opposite sides thereof adapted to seat within openings drilled in the skirt of the piston, the structure being further provided with means whereby positive adjustable separation of the lugs may be obtained at all times.

The invention is illustrated by way of example in the accompanying drawing in which:

Figure 1 is a view in central longitudinal section through a piston having a split skirt and

showing the application of the present invention thereto.

Fig. 2 is a view in longitudinal section through the piston as seen on the line 2—2 of Fig. 1, further disclosing the manner in which the expander is applied.

Fig. 3 is an enlarged view in transverse section showing the exact construction and application of the expander to the piston.

Fig. 4 is an enlarged view in perspective showing the piston expanding device.

Fig. 5 is a view in perspective showing another form of the expanding element.

Fig. 6 is an enlarged view showing the relationship of one of the prongs to an opening in the piston skirt as seen on the line 6—6 of Fig. 3.

Fig. 7 is an enlarged fragmentary view showing the relation of the clamping nut to the expanding ring.

Fig. 8 is a view showing the blank from which the expander is formed.

Referring more particularly to the drawing, 10 indicates an engine piston having a head 11 and a cylinder skirt 12. This skirt is split longitudinally as indicated at 13, the upper end of the split terminating in a transverse split 14.

It is desired to expand the skirt at the split in order to take up wear. In the present instance this is accomplished by a piston expanding device indicated in perspective in Fig. 4 of the drawing and designated by the numeral 15.

This device is shown as applied to the piston skirt in Fig. 1 of the drawing where it will be seen that it spans the split 13, and is fitted with prongs 16 which protrude into openings 18 formed through the skirt of the piston at opposite sides of the slit 13.

The prongs, as shown particularly in Figs. 4 and 8 of the drawing, project from one side of a ring-shaped body member 20. The prongs 16 are struck as part of the blank from which the ring-shaped member 20 is formed and protrude from one side thereof as shown in Fig. 8 of the drawing.

These prongs are arcuate in cross-section and are struck on the same radius as that of the openings 18 into which they extend as shown in Fig. 6 of the drawing.

Attention is directed to the fact that normally the prongs assume a position "above center" of a line passing through the centers of both openings 18. This makes it possible for the prongs to slide along and around the face of the openings when the piston is expanded or when it contracts.

There is always, therefore, an appreciable surface contact between the outer face of the prongs 16 and the faces of the openings 18. This prevents excessive wear and also

allows the parts to move with relation to each other in an easy sliding movement. With reference to Fig. 3 of the drawing, it will be seen that the openings 18 are formed at their outer ends with tapered, countersunk portions 19. The outer ends of the prongs 16 flare outwardly as indicated at 17 to hook into the counterbore and hold the structure in position. The body member is substantially circular in shape when finished and is preferably formed of a piece of flat steel from one side of which the prongs 16 are struck. When finished, the terminating ends of the strip of flat steel are inturned as indicated at 21 and 22 and fit within a channel groove formed at opposite sides of an expansion block 23. This block may be solid as shown in Fig. 4, or may be struck from a single piece of strip material, as indicated in Fig. 5. In any event, channels 24 will occur at opposite sides of the block and will receive the inturned end portions 21 and 22 of the ring 20. These end portions bear against inclined faces 25 of the expanding member 23 so that, as the member 23 is drawn downwardly and between the inturned ends 21 and 22 of the ring 20, the ring 25 will be adjustably expanded by the wedge action. A screw 26 extends through the expanding block and carries a cross member or nut 27 at its inner end. This cross member seats within a recessed edge 28 of the inturned ends 21 and 22 so that the block will be drawn into a wedging position between the members 21 and 22 to produce accurate adjustment of the expander.

Attention is directed to Fig. 7 of the drawing, where it will be seen that the upper face of the nut 27 is tapered. This taper is required to conform to the faces of recesses 28, that have previously been cut into the flat blank, and when the members 21 and 22 have been bent inwardly and radially of the member 20, the wall faces of the recesses will assume a full sliding contact with the inclined faces of the nut 27.

In the operation of the present invention, the expanding structure 15 may be assembled as shown in the drawing, and the skirt of the piston 45 may be prepared by drilling the holes 18 and 19 therein, as shown in Fig. 1 of the drawing, after which the prongs 16 and 17 may be fitted into the holes 18 and 19. The head of the screw 26 is faced downwardly toward the opened end of the skirt and by adjusting the screw any desired amount of expansion may be created as the expansion block 23 is wedged in between the members 21 and 22 of the ring 20, or is retracted. In any event it will be seen that the device may be 55 very inexpensively made, that it may be easily applied to a piston, and that after it has been applied it may be instantly adjusted to create a desired amount of expansion for the skirt of the piston and the necessary fit between the piston 60 and its cylinder. Furthermore, it will be seen that at every point of sliding contact the possibility of binding, friction and wear has been reduced to the minimum.

While I have shown the preferred form of my 65 invention, as now known to me, it will be understood that various changes might be made in the combination, construction and arrangement of parts, by those skilled in the art, without departing from the spirit of the invention as claimed.

Having thus described my invention, what I 70 claim and desire to secure by Letters Patent is:

1. In combination with a piston having a skirt, said skirt being provided with a slit to permit expansion thereof and having openings on both sides of said split, an expansion device comprising a split annular member lying in a plane parallel 5 to the skirt and having a pair of prongs adapted to seat within the openings of the skirt at opposite sides of the slit, yieldable means connecting said prongs, and adjustable means acting between the prongs to separate the same and hold 10 the same in a set position.

2. In combination with a piston having a skirt provided with a slit to permit expansion thereof, an expanding member comprising a split annular member lying in a plane parallel to the piston 15 skirt, means upon opposite sides thereof positively engaging the piston at opposite sides of its split, and means adjustably interposed between the free ends of the split annulus to adjust the positions 20 of the prongs with relation to each other. 20

3. In combination with the split skirt of a piston, said skirt being formed with a pair of openings therethrough, one on each side of the split in the skirt, a piston expander comprising an annular member formed from a strip of flat metal 25 whereby said member will be yieldable circumferentially but substantially rigid laterally, said annular member being split at a point in its circumference, abutments formed at said split ends of the annular member and inclined with relation 30 to each other, an adjustable block interposed between said abutments and having inclined faces, means for adjustably setting said block between said inclined abutments, and a pair of prongs extending from one side of the annular member and 35 adapted to positively engage the piston skirt at opposite sides of its split.

4. In a piston expander of the type described, an annular expanding ring formed of a continuous strip of metal, the opposite ends of which are 40 bent inwardly along radial lines of said ring and are spaced from each other to form an angular throat, a wedge element having inclined faces agreeing with the faces of said inturned members, a screw passing through the center of said wedge 45 element and a nut carried at the lower end thereof formed with faces inclined to bear against the end faces of the inturned portion of the rings.

5. In combination with a piston having a skirt provided with a split to permit expansion thereof, an expanding member comprising a split annulus, a pair of prongs formed at opposite sides of the annular member positively engaging the piston skirt upon opposite sides of said split, a wedge block interposed within the split of the 55 annulus whereby adjustment of the wedge block will increase or decrease the lateral tension upon the piston skirt.

6. In combination with a piston having a skirt formed with a split therein, an annular expanding member having a split within its circumference, an adjustable wedge block disposed within said split, a pair of prongs carried by said annular expanding member and adapted to positively engage the piston skirt at opposite sides of the 65 split and adjusting means associated with the wedge block whereby the tension exerted upon the piston skirt by the prongs may be selectively increased or decreased.

EDWARD B. DENNIE. 70
